Patented June 4, 1918.

FIG. 2.

Richard Johnson

Inventor

By *Geo. P. Kimmel*
Attorney

UNITED STATES PATENT OFFICE.

RICHARD JOHNSON, OF PROCTOR, VERMONT.

FILM-HOLDING SPOOL.

1,268,724.

Specification of Letters Patent.

Patented June 4, 1918.

Application filed September 17, 1917. Serial No. 191,762.

To all whom it may concern:

Be it known that I, RICHARD JOHNSON, a citizen of the United States, residing at Proctor, in the county of Rutland and State 5 of Vermont, have invented certain new and useful Improvements in Film-Holding Spools, of which the following is a specification.

This invention relates to photography and 10 it is the principal aim of the invention to reduce the cost of manufacture of film holding spools to minimum and to so construct the same as to render them exceedingly strong and durable and simplify the construction materially, allowing the film strips to be freely wound and unwound therefrom.

Improvements in the details and arrangement of parts will be apparent from inspection 20 of the accompanying drawings, in connection with the specific description herein-after contained, and wherein the preferred embodiment of the invention is disclosed for the purpose of imparting a full understanding of the same.

25 In the drawings:

Figure 1 is a vertical longitudinal section through the improved spool;

Fig. 2 is an end elevation of the same; and 30 Fig. 3 is detail in perspective of one of the barbed bracing elements.

Having more particular reference to the drawings wherein like reference characters refer to corresponding parts throughout the several views, 1 represents the wooden core 35 of the spool, the same being provided with the usual slot whereby one end of the film strip may be secured to the same. The opposite ends of the core 1 are reduced as at 2 in order that circular end pieces 3 formed 40 of cardboard, pasteboard or other suitable material provided with concentrically arranged openings may be positioned there-over. In this connection, it is to be understood that the diameters of the end pieces 3 45 may be varied to accord to different size film strips, such as conditions or preference may dictate.

As means for securing the circular end pieces to the core 1, I provide metal barbed 50 bracing elements designated in their entireties by the numeral 4, the said elements comprising single pieces of metal having the ends thereof bent at substantially right angles and provided with barbs 5, it being 55 noted that the inner barbs are so arranged

as to permit the embedding of the same in the adjacent portions of the spool core 1, by driving or forcing the same thereinto, while the outer barbs are embedded in the circular end pieces 3 and firmly clamped thereto, 60 by upsetting or bending the same against the inner sides of said end pieces to prevent undue displacement thereof. It will be appreciated, that by providing the elements 4, the circular end pieces 3 will not only be braced 65 in order that the film strip wound about the core 1 will be properly positioned, but also they will serve as means for securely positioning the said circular end strips upon their opposite reduced ends of the core. 70

It is of course to be understood that the usual openings and slots are formed in the cores 1, used in conjunction with the manufacture of my improved spool in order that the same may be properly arranged in a 75 camera and rotated, as desired.

It is well known in the art that the conventional construction of film holding spools include metallic end pieces, which end pieces are secured in various ways to the opposite 80 ends of a wooden core 1, rendering the manufacture of the same somewhat expensive. Therefore, by eliminating the use of metallic end pieces and providing end pieces which are formed of cardboard, paste board or 85 other suitable cheap material and bracing the same so as to render them substantially rigid, the cost of manufacture of the film spools is materially reduced, thus effecting considerable saving and yet, not detracting 90 from the efficiency of the spool in any way.

Manifestly, the construction shown is capable of considerable modification and such modification as is within the scope of my claims, I consider within the spirit of my 95 invention.

I claim:

A film spool including a core, circular end pieces formed of paper or other suitable material arranged on the opposite end extremities of said core, bracing elements having barbed ends arranged diametrically of the end pieces, each element having a barb engaged in the end pieces and a barb engaged in the core, the barb engaged in the end pieces being upset against the inner side of 100 the same. 105

In testimony whereof, I affix my signature hereto.

RICHARD JOHNSON.
